PROTECTIVE MEANS FOR BANKS

Teddy Russell, Pittsburgh, Pa.

Application May 8, 1930. Serial No. 450,829

2 Claims. (Cl. 268—2)

The primary object of this invention is to protect banks and like institutions against bandits and to trap and prevent their escape when attempting a holdup or robbery.

5 The invention provides a shield associated with the teller's window and normally held out of the way, and operable means for interposing the shield between the teller and bandit in an emergency to prevent the consummation of a robbery.

10 The invention furthermore provides a barrier at the usual entrance of the bank which is automatically closable when released to cut off escape of the bandits when apprehended, said barrier being of sectional formation to preclude blocking 15 movement of the barrier and thereby prevent closing of the entrance.

The invention embodies means for automatically actuating the shield and barrier, in an emergency, by pressing a button or similar device, 20 whereby to bring them into operative position, as set forth more fully hereinafter.

While the drawings illustrate a preferred embodiment of the invention, it is to be understood that in adapting the means to meet specific needs 25 and requirements, the design may be varied and changes in the minor details of construction may be resorted to within the scope of the invention as claimed, without departing from the spirit thereof.

30 For a full understanding of the invention and the merits thereof, reference is to be had to the following description and the drawings hereto attached, in which:

Figure 1 is a fragmentary sectional view of a 35 bank illustrative of an applied embodiment of the invention.

Figure 2 is an elevational view of the sectional barrier associated with the entrance to the bank.

40 Figure 3 is an elevational view of the front portion of the teller's booth, showing the shield in conjunction therewith, and the operating means intimately associated with the shield.

Figure 4 is an enlarged sectional view of the 45 restraining means for holding the sections of the barrier retracted.

Figure 5 is an enlarged fragmentary sectional view on the line 5—5 of Figure 3.

Figure 6 is an enlarged fragmentary sectional view on the line 6—6 of Figure 3.

50 Figure 7 is a detail sectional view on the line 7—7 of Figure 6.

Figure 8 is an enlarged sectional view of one of the drums and the clutch associated therewith.

55 Figure 9 is a detail sectional view of a portion of the barrier, on the line 9—9 of Figure 2.

Figure 10 is an enlarged detail sectional view on the line 10—10 of Figure 4.

Figure 11 is an enlarged sectional view on the line 11—11 of Figure 4, looking in the direction of the arrows.

Figure 12 is an enlarged sectional detail on the line 12—12 of Figure 4.

Figure 13 is a detail view of a circuit closer.

Corresponding and like parts are referred to in the following description and designated in the 65 several views of the drawings by like reference characters.

The numeral 1 designates the main entrance to a bank or like institution and 2 the teller's booth or cage having the usual barred or guarded window 3. The numeral 4 designates partitions forming the sides of the booth or cage 2. It is preferred to form the partitions 4 of bullet-proof glass so as not to obstruct the vision and yet prevent smashing of said partitions by a missile or 75 other object coming in contact therewith.

A shield 5 is provided to extend across the window 3 but which normally is held out of the way and below the window. The shield 5 is usually 80 of metal and operates in guides 6 disposed upon opposite sides of the window 3 and secured to the inner side of the front enclosing the booth or cage 2. An expandable helical spring 7 normally tends to project the shield 5 upwardly across the window 3. A rod 8 attached to the shield 5 depends 85 therefrom and is notched adjacent its lower end to receive a latch 9 for holding the shield 5 in lowered position against the action of the spring 7.

The latch 9 is mounted in a bearing 10 and is 90 spring actuated to automatically engage the rod 8 when lowered. A longitudinal shaft 11 is mounted

in the bearing 10 and has a trip 12 pivoted thereto as shown most clearly in Figure 7 of the drawings. The trip 12 extends across the path 95 of the latch 9 and, in consequence, rotation of the shaft 11 in one direction moves the latch 9 to release the rod 8, which permits the spring 7 to come into play and shoot the shield 5 across the window 3. By having the trip 12 pivoted, reverse movement of the shaft 11 is provided for without 100 damaging any of the mechanism.

An electric motor 13 is geared to the shaft 11 and is included in a circuit which may be closed from any one of a number of determinate points. Figure 13 of the 105 drawings, illustrates a push button 14 within convenient reach of the teller and which may be operated in an emergency to close the circuit of the motor 13, whereby to rotate the shaft 11 and effect release of the shield 5, which is thereupon projected across the window 3.

The shield 5 is adapted to be retracted or returned to normal position to uncover the window 3, by means including cables 15, drums 16, loose on the shaft 11, and a clutch mechanism between 5 each of the drums 16 and the shaft 11. This clutch mechanism includes a fixed clutch member 17 and a movable clutch member 18 which is splined to the shaft 11, as indicated most clearly in Figure 8 of the drawings. A shipper lever 19 10 coacts with each of the cables 15 and movable clutch members 18 to throw the drums 16 into or out of clutched engagement with the shaft 11. Each of the cables 15 is provided with fixed stops 20 and 21 disposed to engage opposite sides of an 15 arm of the shipper lever 19. When the shield 5 is lowered or occupies a position to uncover the window 3 or other opening, the clutches are disengaged, as indicated most clearly in Figures 3 and 8 of the drawings. When the shield 5 is elevated or 20 projected across the opening, the stops 21 engage the lever 19 and move the same to throw the clutches into engagement so that when the shaft 11 is rotated in a reverse direction, the drums 16 are likewise rotated to wind the cables 15 thereon and 25 draw the shield 5 downward so as to uncover the window 3 or other opening. When the shield 5 is withdrawn, the stops 20 engage the shipper levers 19 and disengage the clutch members 18 from the clutch members 17, thereby releasing 30 the drums 16.

The entrance 1 is adapted to be closed by a door 22 which, preferably, is of sectional formation, as indicated most clearly in Figure 2 of the drawings. The longitudinal edges of the sections 35 are connected by means of a tongue and groove joint, as indicated most clearly in Figure 9 of the drawings. A dog or catch 23 is pivoted to the inner end of a section and is adapted to engage a stop on the adjacent section with the result that a rearward movement of an upper section effects a corresponding movement of the adjacent section therebelow while, at the same 40 time, admitting of the upper section moving forward to close the opening while the next section therebelow may be retarded by an obstruction, as indicated at 24 in Figure 2. In the event of a log 24 or other obstruction being placed to prevent closing of the door or barrier, the section 45 above the log 24 will close, whereas the section engaging the log will be retarded by contact therewith, as indicated most clearly in Figure 2 of the drawings. Removal of the log 24 releases the obstructed sections and the same will 50 then be moved to closed position by the springs acting thereon. A spring 7a is provided for each 55 of the sections of the door or barrier 22. A rod 8a is also attached to each of the sections and is notched adjacent its free end to engage a latch 9a, whereby the sections comprising the barrier 60 are held retracted or in withdrawn position, as indicated in Figure 1 of the drawings. The latch 9a consists of a bar and is mounted in a vertically disposed bearing 25 to move laterally to engage 65 or disengage the rod 8a. A vertical shaft 26 mounted in the bearing 25 is geared at its lower end to the longitudinal shaft 11 and is provided adjacent its upper and lower ends with pivoted 70 trips 12a whereby to engage the ends of the latch 9a and move it laterally to release the rods 8a

and permit the sections comprising the barrier 22 to be projected across the opening forming the entrance 1. Duplicate drums 16 are loose upon the vertical shaft 26 and are adapted to be clutched thereto by members 17 and 18 identically as the like previously described members cooperate with the longitudinal shaft 11, the drums being connected with the closure 22 by a second set of cables 15 provided with stops for shifting the levers 19, as will be understood on reference to Fig. 2.

Under normal conditions, the barriers or protectors 5 and 22 are withdrawn or retracted to expose the openings 1 and 3. It is understood that the springs 7 and 7a are compressed and held in restraint by the rods 8, 8a and cooperating latches 9 and 9a. In the event of a robbery being attempted, pressure upon the button 14 or like part, closes the circuit including the motor 13, whereupon the shafts 11 and 26 are rotated. During the initial rotation of these shafts, the trips 12 and 12a carried thereby, effect release of the latches 9 and 9a, with the result that the springs 7 and 7a being released, project the barriers into operative position. As a result, the teller is protected and the bandit or bandits prevented from escaping. As the barriers or closures reach the limit of their forward movement, the stops 21 on the cables 15 engage and operate the levers 19 whereby to clutch the drums 16 to the respective shafts 11 and 26, so that upon reversing the motor 13, the cables 15 previously unwound from the drums are wound thereon and return the barriers or closures to normal position. As the closures reach the limit of their return movement, the stops 20 on the cables 15 operate the levers 19 and release the drums 16 so that in the next emergency a repetition of the operation just described may be effected. A plate 14a 105 extends over the push button 14 to present a large 110 surface to be engaged by the teller or other person, thereby assuring operation of the push button in an emergency. This plate is pivoted and spring actuated to normally stand away from the 115 button 14.

What is claimed is:

1. A protector operating mechanism including a latch, a motor driven shaft, a trip pivoted on the shaft for actuating the latch, a motor for operating the shaft, a drum loose on the shaft, a clutch between the drum and the shaft, a cable for connecting the protector with the drum, a shipper lever for throwing the movable clutch member into and out of engagement with the drum, and a stop on the cable for operating the shipper lever to throw the drum into and out of clutched engagement with the shaft.

2. A protector operating mechanism including an arm extending from the protector, a latch arranged to engage said arm and extending beyond the same, a motor driven shaft, and a trip pivoted to the shaft and extending across the path of the latch whereby upon movement of the shaft in one direction the latch will be released and upon movement of the shaft in the opposite direction the trip will yield and ride past the latch.

TEDDY RUSSELL. [I.S.]
